CHIMNEY FLUE DAMPER

Harold Spry Woods, Portsmouth, N. H.

Application December 9, 1937, Serial No. 178,962

1 Claim. (Cl. 126—292)

My invention relates to improvement in chimney flue dampers in flues that are connected to all types of furnaces and boilers that are in general use for the heating of buildings of whatever character and for whatever purpose, and to improvements in chimney flue dampers in flues connected to steam boilers wherein steam at low pressure is generated for commercial purposes; but it is not applicable on chimneys connected to 10 high-temperature industrial furnaces nor to chimneys connected to high-pressure steam boilers. My chimney flue damper is operated automatically, electrically, and mechanically; the damper is opened automatically by electrically-motivated commercial mechanism when a commercial thermostat or commercial boiler control or a commercial furnace control operates to close an electric circuit, and the damper is closed by the action of a coil spring under tension.

The objects of my improvement are; first, to afford a device to apply draft to a fire in a manner recommended by combustion engineers of note, to provide a device for applying draft to a 20 fire only when needed, third, to provide a device to reduce the draft to a predetermined minimum when solid fuels are being burned under conditions commonly designated as a period of "bank," fourth, to provide means for completely stopping 25 draft in the flue that is serving automatic oil burners or automatic gas burners, fifth, to provide a device for connecting instantaneously the chimney and the flue serving either a hand-fired coal fire, or an automatic coal stoker, or an automatic oil burner, or an automatic gas burner, sixth, to provide a device that will prevent cold air or an excess amount of cold air being sucked 30 through the furnace setting or the boiler setting by the "pull" of the chimney during the period 35 when the automatic oil burner or the automatic gas burner is idle, or when the solid fuel fire is on "bank," seventh, to afford a device in which the friction opposing the rotation of the damper is greatly reduced, eighth, to provide means for 40 delaying the start of full combustion until the damper is at least two-thirds open.

I attain these objects by mechanism illustrated in the accompanying drawing, in which:

Figure 1 is a front view of the entire machine showing the assembled parts.

Figure 2 is a side view of the entire machine with a section of the specially-constructed flue removed to show the position of angle iron segments in relation to the damper when they are used to close the flue completely as in the case

of automatic oil burner or automatic gas burner installations during the periods of inactivity.

Figure 3 is a plan view of the entire machine.

Figure 4 is an enlarged perspective view of a portion of the damper plate and shows the slots into which the axis fits.

Figure 5 is an enlarged view of the gear that changes the straight-line motion of the engaging rack, connected to a commercial solenoid, to rotary motion.

Figure 6 is an enlarged view of the guide for the untoothed portion of the part shown in Figure 5.

Figure 7 is an enlarged view partly in section showing the bearing for the damper plate axis.

Figure 8 is an enlarged view of the axis that moves in the conical recess shown in Figure 7.

Figure 9 is an end view of Figure 8 and shows a slot into which the damper plate is inserted.

Figure 10 is a section on the line 10—10 of Figure 6 and shows the recessed path for the untoothed portion of the gear shown in Figure 5.

Similar numerals refer to similar parts throughout the several views.

The flue 1 is of regulation length, and it must be of $\frac{1}{16}$ inch or heavier black sheet metal in order to provide the required degree of stiffness; ordinary sheet metal used in flues is too flimsy for the purposes. The bearing 2 and the bearing 6 are both brazed to flue 1 and at exactly opposite ends of the same diameter of the flue. Legs or posts 14 are brazed to the flue and they are located approximately as shown in Figure 1. All of the above-mentioned parts taken together constitute the framework of the machine.

Bearing block 3, threaded and recessed on the damper end thereof to form a conical recess whose apex angle is ninety degrees, screws into bearing 2; and axis 4 with a conical end forming an angle of sixty degrees moves in the recess in bearing block 3. Axis 5 is attached to damper plate 8 and diametrically opposite axis 4 and extends through bearing 6 and sleeve 7 and continues as a drive shaft terminating in a square end to which gear 11 is attached. Sleeve 7 screws over bearing 6 and acts as a packing sleeve. Damper plate 8 is a circular disk of a diameter smaller than the diameter of the flue 1. Semi-circular angle irons 9 are attached to the flue 1 only when an automatic oil burner or automatic gas burner is being served by the flue, and they then help to close completely the free area of the flue during the idle periods of the oil burner or gas burner.

Posts 14 support a platform 13 made of trans-

ite, a commercial product, to which a suitable commercial solenoid 12 is attached by posts 17. Posts 14 are threaded over a length sufficient to allow bringing the solenoid 12 into proper alignment with the end of the drive shaft 5, and in platform 13 holes elongated parallel to the length of flue 1 to receive posts 14 and for posts 17 other holes elongated in a direction perpendicular to the length of the flue 1 in connection with the extra threads on the posts 14 allow adjustment of the location of solenoid 12 in any one or in all three mutually perpendicular directions. Thus, solenoid 12 can be located at exactly the proper point to function correctly with the rack 15, gear 11 and guide 10.

Fitting over the square end of shaft 5 is the gear 11 and its teeth mesh with teeth on rack 15. Rack 15 is attached to the plunger in solenoid 12 and moves in a straight line direction under the impulsion of the plunger in solenoid 12, this straight line motion being converted to rotary motion by gear 11. It will be observed that the gear 11 is but slightly more than a quadrant of a circle of equal diameter. This design is occasioned by the necessity of selecting such a diametral pitch as will rotate the gear 11 and the damper plate 8 through ninety degrees of arc within the travel distance of the plunger in solenoid 12.

The guide 10 has one long limb and a shorter second limb, the end of the long limb being attached in any suitable manner to the upper end of the rack bar 15 and said rack bar is formed with a notch 15' in one edge thereof which receives the end of the short leg, as shown in Figure 1. The bight of the guide has a groove or channel therein for receiving the hub of the gear 11. The pintle 4 is formed with a slot 4' in its inner end which divides said inner end into a pair of prongs which fit into the slots 6' of the damper plate, see Figure 4. The prongs are fastened in the slots 6' in any suitable manner. The inner end of the shaft which carries the gear 11 and which forms the axis 5 is connected to the damper plate in the same manner.

When automatic combustion devices of any manufacture and/or type are used in conjunction with this chimney flue damper, I recommend the use of a mercury switch of commerce. Switch arm 16, equipped with a fuse clip, is attached to shaft 5 in such a manner that the switch arm 16 rotates parallel to and in unison with shaft 5, thus opening and closing the mercury switch and thus opening and closing the electric circuit. Also, switch arm 16 is attached to shaft 5 in such manner that the mercury switch cannot close the electric circuit until shaft 5 has rotated to a position where the damper plate 8 to which shaft

5 is attached is about two-thirds open, when enough of the chimney will be available for service to the combustion gases, or gases of combustion. In these cases, two electric circuits in parallel are used; one circuit contains the automatic combustion device, and the other circuit contains common commercial controls such as thermostat, etc. and this chimney flue damper machine.

When the chimney damper is wide open and when the electric circuit is broken by the action of any one of the commercial controls such as thermostat, etc. the demands for heat have been satisfied and the damper plate 8 should be closed. Closing of the damper plate 8 is accomplished by the action of a coil spring 18 attached to the plunger in solenoid 12 and to a post fastened to platform 13, and having a tensile force sufficient only to overcome the friction and inertia of the moving parts of the chimney flue damper machine.

The damper plate 8 is designed with a diameter of the flue 1 to provide an annular space between the flue 1 and the circumference of the damper plate 8 when the damper plate 8 is in the closed position. The area of the annular space, above mentioned, is that area necessary to allow a predetermined minimum volume of the gases of combustion to escape into the chimney during the period when the coal fire, whether stoked or hand-fired, is "banked," i. e., the rate of combustion of the coal is retarded.

I am aware that, prior to my invention, mechanically and/or electrically operated dampers have been made to operate on some automatic principle. I, therefore, do not claim such a combination broadly.

I claim:

A damper device of the class described comprising a pipe section for insertion in a pipe line leading from a furnace to a chimney, a damper in the pipe section including a shaft having one end extending from the pipe section, a segmental gear connected to the extended end of the shaft, posts extending outwardly from a part of the pipe section, a platform of non-conducting material supported by the outer ends of the posts, a solenoid, posts supporting the same from the platform, a plunger passing through the solenoid and having one end extended and formed with rack teeth for engaging the teeth of the gear, spring means connected with the other end of the plunger for normally holding the plunger in a position with the damper closed and a substantially U-shaped guide member connected with the toothed part of the plunger and having a groove in its bight part for receiving portions of the hub of the segmental gear.

HAROLD SPRY WOODS.
